US0D1069525S

(12) **United States Design Patent** (10) Patent No.: **US D1,069,525 S**
Zhou (45) Date of Patent: ** Apr. 8, 2025

(54) **TOMATO CAGE**

(71) Applicant: **Changzhou GelaiMeiInternational Trade Co., Ltd.**, Changzhou (CN)
(72) Inventor: **Jiao Zhou**, Changzhou (CN)
(73) Assignee: **Changzhou GelaiMeiInternational Trade Co., Ltd.**, Changzhou (CN)

(**) Term: **15 Years**

(21) Appl. No.: **29/923,719**

(22) Filed: **Jan. 1, 2024**

(51) LOC (15) Cl. **08-01**

(52) U.S. Cl. USPC **D8/1**

(58) **Field of Classification Search**
